a corporation of Delaware

Application November 2, 1943, Serial No. 508,720

9 Claims. (Cl. 22—57)

The present invention relates to the art of producing cast metal bodies.

In the electric fusion method of producing cast metal bodies such as ingots, a consumable electrode containing some or all of the metal ingredients of the ingot to be produced, has one end submerged in a protective layer of flux in a mold. Current discharged through a gap separating this electrode from the body of deposited molten metal creates a metal fusing zone, so that said electrode, as well as other metal ingredients which may be fed in this zone, are fused and deposited as molten metal below the flux layer. This electrode passes through a contact sleeve or nozzle which supplies metal fusing current to the electrode, and which extends into the mold above the flux layer. As the electrode is consumed, it is fed endwise with respect to the contact nozzle to maintain a constant positional relationship between the current discharge end of the electrode and the surface of the deposited molten metal. As the level of the molten metal in the mold gradually rises, the level of the flux also rises to the same extent. It is necessary, under these conditions, to raise the contact nozzle to maintain a predetermined positional relationship between the lower end of the nozzle and the upper surface of the flux. If the contact nozzle approaches too close to the hot flux layer, the intense heat in said layer may cause destruction of the contact nozzle.

When the mold is of comparatively large cross-section, a pilot control may be employed therein to move automatically the contact nozzle, so that its lower end will be maintained a constant predetermined distance above the surface of the flux layer. However, when the cross-section of the mold is small, it is difficult to use the pilot control because of the limited clearance afforded by said mold.

One object of the present invention is to provide a new and improved control means which maintains a constant positional relationship between the contact nozzle and the flux layer in a mold, and which is entirely outside the mold cavity.

Various other objects of the invention will be apparent from the following particular description, and from an inspection of the accompanying drawing, which shows somewhat diagrammatically partly in vertical section and partly in front elevation a casting apparatus having nozzle control means embodying the present invention.

Referring to the drawing, there is provided a 55 electrode, passes through the gap 17, and there-

mold 10 which may be of any suitable hollow shape in accordance with the desired shape of the cast body to be produced, but which is shown in the form of an upright cylindrical tube having 5 an elongated cavity 11 of comparatively small cross-section. This mold 10 is desirably of a metal having high heat conductivity such as copper, and is provided with a jacket 12 for the circulation of a suitable cooling liquid therethrough. 10 An inlet pipe 13 for the cooling liquid is shown connected into the upper end of the mold jacket 12. An outlet pipe (not shown) for the cooling liquid may be connected to the lower end of this mold jacket 12.

15 The lower end of the mold 10 may be closed by any suitable means, as for example a stool (not shown), also of metal such as copper, and also desirably hollowed to form a jacket for the circulation of a suitable cooling liquid therethrough.

20 The metal is produced and deposited in the mold 10 by the use of a flux submerged electrode device which may be of the general type shown in my U. S. Patent No. 2,191,479, issued February 25, 1940. For that purpose, there is provided a consumable electrode 14 extending in the mold 10. Electrode 14 may be solid and contain all of the constituents of the desired metal 15 or electrode 14 may be hollow and be made of some 25 of the constituents of metal 15 while the remainder of the constituents are supplied through electrode 14 to the fusion zone created at the discharge end of electrode 14 at controlled rates in the fluent form of granules, pellets, powders, and the like. The rate of supply of electrode 14 and the rate of supply of the material in fluent form 30 being adjusted to produce a metal 15 in the mold 10 having the required analysis.

The lower end of the electrode 14 is submerged 40 in a floating layer or blanket 16 of flux of any suitable composition having the proper electrical and metallurgical characteristics and is spaced above the upper surface of the deposited metal 15 by a gap 17. This flux 16 refines the metal as it is produced, promotes fusion of the metal, protects it against atmospheric contamination, and insulates its top surface against rapid heat loss. For that purpose, flux 16 may comprise silicates or components of silicates, such 45 as manganese silicate, calcium silicate, aluminum silicate, glass and the like.

The electrode 14 and the deposited metal 15 are electrically connected in the same circuit, so that current as it is discharged from said electrode, passes through the gap 17, and there-

by creates a high temperature zone in which the solid metal ingredients are readily fused. The electrical connection to the electrode 14 is effected through a contact nozzle 18 connected to a suitable source of current, and embracing the electrode 14 with a snug slide fit loose enough to permit the feeding of said electrode through said nozzle, but tight enough to maintain electrical contact between said nozzle and said electrode.

The electrical connection of the deposited metal 15 into the circuit of the contact nozzle 18 may be effected as for example, by grounding the metal walls of the mold 10.

The contact nozzle 18 serves not only as a means of maintaining a steady current feed to the electrode 14, but also serves as a feed guide for said electrode. The lower end of this contact nozzle 18 is spaced a substantial distance above the upper level of the flux 16 to prevent said nozzle from being destroyed by the intense heat of the superheated flux 16.

As the metal producing operation progresses, the level of the deposited metal 15 as well as that of the flux layer 16 gradually rises. As the electrode 14 is consumed and the deposited metal 15 rises, said electrode is moved at a rate necessary to maintain the current discharge gap 17 constant in length. This controlled movement of the electrode 14 may be effected in any well-known manner, as for example through a pair of feed wheels 20 on opposite sides of the electrode 14 and in frictional engagement therewith. At least one of these feed wheels 20 is driven from a motor 22 through a suitable reduction gearing, while the other wheel may be positively driven from said motor or may be merely an idler. Motor 22 may be controlled, for example, by the voltage drop across the gap 17 in any well-known manner, as is common in the electric arc welding and electric arc furnace arts, so that the feed wheels 20 are automatically operated and controlled to feed the electrode 14 as necessary to maintain a discharge gap 17 of constant length.

As the level of the flux 16 gradually rises, it is necessary to move the contact nozzle 18 upwardly to an extent necessary to maintain a constant positional relationship between the lower end of said contact nozzle and said flux layer. For moving the contact nozzle 18 upwardly, said nozzle is secured to a hoist 23 by any suitable means, as for example through a clamp 24. This hoist 23 may be moved vertically by any suitable means. Thus, hoist 23 may be moved in the manner indicated in the drawing through a pair of vertical feed screws 26 threaded therein, and journaled in suitable fixed bearings 27 arranged to hold these feed screws against axial movement. The two feed screws 26 are driven in unison and in the same direction through a motor 28 and a speed reducing transmission between said motor and said feed screws. This transmission, for example, may comprise worm wheels 30 keyed or otherwise affixed to feed screws 26 respectively for rotation therewith, and meshing with respective worm wheels on the shaft of the motor 28.

As a feature of the present invention, the operation of the motor 28 is automatically controlled by means of a thermo-responsive control device disposed entirely outside of the mold cavity 11. This control device is desirably of the electric pyrometric type having a heat sensitive element enclosed in a contact shoe or hous-

ing 35 in the mold jacket 12. This contact housing 35 is in slide engagement with the outer surface of the inner metal mold wall 36, and the thermo-sensitive element therein is in slide contact with this surface, or at least in close proximity thereto to react thermally upon changes in temperature in the mold cavity 11 at the level of said element.

10 The control device is advantageously of the thermocouple type, so that the thermo-sensitive element in the contact shoe 35 would be the hot junction or couple of the device, although as far as certain aspects of the invention are concerned, the control device may be of any other suitable type, as for example of the electrical resistance type, in which case the thermo-sensitive element in the contact shoe 35 would be the resistance element of the device.

15 Connected to the contact shoe 35 is a conduit 38 through which the leads 37 from the thermocouple or junction extend. These leads 37 are sealed and insulated from the cooling liquid in the mold jacket 12, and connect into a control unit 39. This control unit 39 may be of any 20 well-known type, in which the generated thermo-electric current when increased in strength above a predetermined value, closes a switch (not shown) in the circuit of the hoist motor 28 and thereby operates said motor, and when it falls below a predetermined value opens this switch 25 and thereby shuts off said motor. The motor 28 for that purpose is connected to this control unit 39 by the leads 40.

20 Contact shoe 35 is positioned to maintain the 30 bottom end of contact nozzle 18 the chosen distance above the top surface of the hot flux or slag 16. In operation, since the volume of metal 15 constantly increases the level of flux 16 constantly rises and when the top surface of this 35 flux 16 reaches a position near or opposite the level of the thermocouple in the contact shoe 35, as shown, the intense heat of the flux is transmitted to the thermocouple through the metal mold wall 36. This results in the generation of 40 thermo-electric current above a predetermined value, and the consequent closing of the circuit of the motor 28. The motor 28 will therefore rotate in a direction to raise the hoist 23 through the feed screws 26 so that the contact nozzle 18 45 is raised. At the same time, the contact shoe 35 is raised in unison with the contact nozzle 18, so that when said contact shoe reaches that position above the intense heated area defined by the flux 16, at which the generated thermo-electric current falls below a predetermined value, the motor 28 shuts down.

50 For effecting the movement of the contact shoe 35 in unison with the contact nozzle 18, the lead conduit 38 extends through a stuffing box 42 on the upper end of the mold 10, and is connected to the hoist 23 by any suitable means, as for example by means of a clamp 43. This stuffing box 42 forms a fluid-tight slide bearing for the conduit 38.

55 By means of the construction described, the lower end of the contact nozzle 18 is maintained at a constant positional relationship with respect to the flux 16, so that at no time will this contact nozzle become overheated or will it in any way dip into said flux.

60 The feed device 20 and 22 for the electrode 14 may, if desired, be supported on the hoist 23 as shown. With this construction, the electrode 14 will be moved upwardly with the contact nozzle 18, but will still be subject to the control of the 65

feed wheels 20 according to the voltage drop across the gap 17, or according to any other regulating factor selected, so that the length of this gap will be kept substantially constant.

Although the invention is shown in conjunction with a control by which the contact nozzle 18 and the thermocouple conduit 36 are raised from a stationary mold 10 while the casting operation progresses, as far as certain aspects of the invention are concerned, the contact nozzle 18 as well as the conduit 36 with its contact shoe 35 may be kept stationary, while the mold 10 is lowered by some control device similar to that shown to maintain a constant positional relationship between the contact nozzle 18 and the flux 16.

Also, in accordance with certain aspects of the present invention, instead of controlling the motor 28 by alternately turning it off and on, said motor can be regulated by controlling its speed to maintain the desired position of the contact nozzle 18 relative to the flux 16. This motor 28 may be of the reversible type to permit the hoist 23 to be lowered for each new casting operation. The reversing circuit for this motor 28 may be of any type well-known in the art.

As many changes can be made in the above apparatus, and many apparently widely different embodiments of this invention can be made without departing from the scope of the claims, it is intended that all matter contained in the above description or shown in the accompanying drawing shall be interpreted as illustrative and not in a limiting sense.

What is claimed is:

1. A casting apparatus comprising a mold with a metal wall confining the mold cavity, a current discharge electrode adapted to extend into said mold with its lower end submerged in a layer of flux, a contact nozzle for said electrode adapted to extend into said mold above said flux, a thermo-responsive element on the outside of said mold cavity adjacent to said wall, and means for translating the action of heat of predetermined intensity on said element into a corresponding motive force, whereby axial movement of said contact nozzle relative to said mold can be controlled in accordance with said force to maintain said nozzle a substantially constant distance above said flux.

2. A casting apparatus comprising a mold with a metal wall confining the mold cavity, a current discharge electrode adapted to extend into said mold with its lower end submerged in a layer of flux, a contact nozzle for said electrode adapted to extend into said mold above said flux, and thermometric control means for automatically maintaining substantially constant the positional relationship between said contact nozzle and the flux in said mold, said control means comprising a thermo-responsive element on the outside of said mold cavity adjacent to said wall.

3. A casting apparatus comprising a mold with a metal wall confining the mold cavity, a current discharge electrode adapted to extend into said mold with its lower end submerged in a layer of flux, a contact nozzle for said electrode adapted to extend into said mold above said flux, and control means for automatically maintaining constant the positional relationship between said contact nozzle and the flux in said mold, said control means comprising a thermo-responsive element on the outside of said cavity adjacent to said wall, a motor for causing relative axial movement between said mold and said contact

nozzle, and means responsive to the thermal reaction of the flux on said element for controlling the operation of said motor.

4. A casting apparatus comprising a mold with a metal wall confining the mold cavity, a current discharge electrode adapted to extend into said mold with its lower end submerged in a layer of flux, a contact nozzle for said electrode adapted to extend into said mold above said flux, a thermo-responsive element on the outside of said mold cavity adjacent to said wall, means for translating the action of heat of predetermined intensity on said element into a corresponding motive force, whereby axial movement of said contact nozzle relative to said mold can be controlled in accordance with said force to maintain said nozzle a substantially constant distance above said flux, and means interconnecting said nozzle and said thermo-responsive element for movement in unison relative to said mold.

5. A casting apparatus comprising a mold with a metal wall confining the mold cavity, a current discharge electrode adapted to extend into said mold with its lower end submerged in a layer of flux, a contact nozzle for said electrode adapted to extend into said mold above said flux, control means for automatically maintaining constant the positional relationship between said contact nozzle and the flux in said mold, said control means comprising a thermo-responsive element on the outside of said cavity adjacent to said wall, a motor for causing relative axial movement between said mold and said contact nozzle, and means responsive to the thermal reaction of the flux on said element for controlling the operation of said motor, and means interconnecting said thermo-responsive element and said contact nozzle for movement in unison relative to said mold.

6. A casting apparatus comprising a mold with a metal wall confining the mold cavity, a current discharge electrode adapted to extend into said mold with its lower end submerged in a layer of flux, a control nozzle for said electrode adapted to extend into said mold above said flux, a shoe in slide contact with the outer surface of said wall, a thermo-responsive element in said shoe in close proximity to said wall to react readily when the flux reaches a position near the level of said element, means for translating the action of heat of predetermined intensity on said element into a corresponding motive force, whereby axial movement of said contact nozzle relative to said mold can be controlled in accordance with said force to maintain said nozzle a substantially constant distance above said flux, and means interconnecting said nozzle and said shoe for movement in unison relative to said mold.

7. A casting apparatus comprising a mold with a metal wall confining the mold cavity, a current discharge electrode adapted to extend into said mold with its lower end submerged in a layer of flux, a control nozzle for said electrode adapted to extend into said mold above said flux, control means for automatically maintaining constant the positional relationship between said contact nozzle and the flux in said mold, said control means comprising a shoe in slide contact with the outer surface of said wall, a thermo-responsive element in said shoe in close proximity to said wall to react readily when the flux reaches a position near the level of said element, a motor for causing relative axial movement between said mold and said contact nozzle, and means re-

sponsive to the thermal reaction of the flux on said element for controlling the operation of said motor, and means interconnecting said shoe and said nozzle for movement in unison relative to said mold.

8. A casting apparatus comprising a mold with an inner metal wall and an outer wall forming therebetween a jacket for the circulation of a cooling liquid therethrough, a current discharge electrode adapted to extend into said mold with its lower end submerged in a layer of flux, a contact nozzle for said electrode adapted to extend into said mold above said flux, and control means for automatically maintaining constant the positional relationship between said contact nozzle and the flux in said mold, said control means comprising a thermo-responsive element in said jacket adjacent to said inner wall, a motor for causing relative axial movement between said mold and said contact nozzle, and means responsive to the thermal reaction of the flux on said element for controlling the operation of said motor.

9. An apparatus for producing ingots comprising

ing a mold, an inner metal wall and an outer wall forming therebetween a jacket for the circulation of a cooling liquid therethrough, a current discharge consumable electrode adapted to extend into said mold with its lower end submerged in a layer of flux, a contact nozzle for said electrode adapted to extend into said mold above said flux, thermocouple control means for automatically maintaining constant the positional relationship between said contact nozzle and the flux in said mold, said control means comprising a shoe in slide contact with the outer surface of said inner wall, a thermocouple in said shoe in close proximity to said wall to react readily when the flux reaches a position near the level of said element, a motor for causing relative axial movement between said mold and said contact nozzle, and means operable when the thermoelectric current generated in said thermocouple exceeds a predetermined value for operating said motor in a direction to raise said nozzle, and means interconnecting said nozzle and said shoe for controlled movement in unison.

ROBERT K. HOPKINS.
